UNITED STATES PATENT OFFICE.

FRANK E. DAVIS, OF LA CROSSE, WISCONSIN, ASSIGNOR TO LA CROSSE PLOW CO., OF LA CROSSE, WISCONSIN, A CORPORATION OF WISCONSIN.

PLOW.

1,130,714.

Specification of Letters Patent.

Patented Mar. 9, 1915.

Application filed December 12, 1913. Serial No. 806,148.

To all whom it may concern:

Be it known that I, FRANK E. DAVIS, a resident of La Crosse, in the county of La Crosse and State of Wisconsin, have invented certain new and useful Improvements in Plows, of which the following is a full, clear, and exact description.

The invention relates to plows.

In the operation of plows in which the shares are raised and lowered by mechanism including a crank connected to the furrow-wheel at one side of the plow, it is customary to angle the spindle vertically to render the furrow-wheel effective to overcome side pressure, and it is desirable at times to angle the spindle horizontally to give the wheel more or less "lead" away from land, to counteract side pressure.

The invention relates more particularly to the mechanism for adjusting and controlling the position of the wheel-spindle of these furrow-wheels.

One object of the invention is to make provision for controlling the wheel spindle, so that its horizontal or vertical angle will not be changed when the crank-arm between the wheel and the plow-carrying structure is shifted, so that despite variation in the position or swinging of the crank, the angle of the wheel-spindle with respect to the horizontal or vertical will remain unchanged.

Another object of the invention is to provide improved means for adjusting the horizontal angle of the wheel-spindle to give it more or less lead.

Other objects of the invention will be apparent from the structure hereinafter set forth.

The invention consists in the several novel features hereinafter set forth and more particularly defined by claims at the conclusion hereof.

In the drawings: Figure 1 is a plan of a plow embodying the invention. Fig. 2 is a side elevation. Fig. 3 is a perspective of the wheel spindle for the side furrow-wheel and its connections to the plow-carrying structure. Fig. 4 is a horizontal section through the bracket in which the wheel-spindle is adjustably held, the spindle being shown therein.

The invention is shown as applied to a gang-plow comprising a carrying structure

consisting of plow-beams 10, which are secured together at their rear ends by braces 11 and at their front ends by brackets 12 to which the draft-connection is secured. A plowshare 14 is secured to each beam 10. A land-wheel 15 is mounted on a spindle 16 on the outer end of a crank-arm 17 on a shaft 18, which is mounted in suitable bearings 19 which are secured to the beams 10, respectively. The rear of the plow is sustained by a trail-wheel 20 which is suitably mounted at the rear end of an arm 21 on a standard 22, which is pivotally held in a bracket 23, which is secured to one of the plow-beams 10 by bars 24. The furrow-side of the plow is sustained by a furrow-wheel 27, which is operatively connected to the carrying-structure by means, including a crank-arm 28 on a shaft 29, which is journaled in bearings 30 on two of the beams 10.

Mechanism is provided for rocking both of the shafts 18 and 29 conjointly to raise and lower the plow-carrying-structure and this mechanism comprises a main lever 32 which is rigid on shaft 18 and is adapted to be locked in different positions by means of a lock-bolt 33 and a segmental rack 34 which is rigidly secured to one of the plow-beams 10. The operating connection between the main lever 33 and the crank-shaft 29, to which the side furrow-wheel is connected, comprises a lever 36 which is pivoted at 37 to lever 32, and a link 38 which is pivoted to lever 36, at 39, and to an arm 38' which is rigid on shaft 29. By adjustment of lever 32 along rack 34, the depth to which the shares are lowered may be varied. Lever 36 serves to effect adjustment of the furrow-wheel, relatively to the land-wheel, being normally locked to a rack 41, which is rigid on the main lever 32 by a lock-bolt 42 carried by said lever. In operation, shift of lever 32 will raise or lower shafts 18 and 29 simultaneously to raise or lower both sides of the plow-carrying structure and the plows carried thereby. This mechanism thus exemplifies mechanism for operating the crank-arm 28 to raise or lower the plow-carrying structure.

In practice, the axis of the furrow-wheel 27 is usually angled vertically to cause the wheel to resist sidewise movement toward land, resulting from pressure of the soil upon the plows and sometimes it is also

necessary to angle the axis of this furrow-wheel horizontally to give the wheel more or less "lead" away from land according to the character of the soil being plowed. 5 When the spindle for the side furrow-wheel has a crank-arm connected thereto, adjustment of the crank-arm, resulting from shift of the operating mechanism to cause the plow-share to travel at different depths, 10 varies the angle of the spindle or axis of the wheel to give it more or less inclination vertically and horizontally. To prevent this variation, wheel-spindle 45, on which furrow-wheel 27 is journaled, is fixed in a bracket 46, in which the out-turned end 28' of crank-arm 28 is pivoted, and the verticality of this bracket is maintained or the bracket is caused to move vertically without rotation, by a link 47, which has one of its 15 ends pivoted in bearing 30 and its other end in a lug 48 at the upper end of bracket 46, this link being substantially parallel to the crank-arm 28 on operating shaft 29. As a result of this construction, bracket 46 and 20 wheel-spindle 45 will maintain their assigned vertical and horizontal angle despite pivotal movement of the shaft 29 and crank-arm 28 in adjusting the plow-carrying structure, so that the angle of the wheel-spindle 25 45 will not be varied during the operation of the plow-shifting mechanism.

The invention provides improved means for varying the horizontal angle of the wheel-spindle 45, so that the tendency of the 30 furrow-wheel to counteract side pressure may be varied, and for this purpose, the bearing for the wheel-spindle 45 in bracket 46 is flared or elongated at one end, and adjusting-screws 51 and 52, at the front and 35 rear of said bearing, are adapted to shift the wheel-spindle angularly and horizontally by tightening one of the screws and loosening the other. A set-screw 53, at the inner end of bracket 46 is adapted to secure 40 the spindle against longitudinal movement and by loosening all of the screws slightly, the spindle 45, together with the furrow-wheel 27, may be adjusted bodily and laterally to travel at the desired point in the previously cut furrow.

The invention thus exemplifies a plow in which the carrying-frame or structure is connected to one of the furrow-wheels by means of a crank-arm and in which the angle 55 of said wheel is not disturbed by rocking of the crank-arm to raise and lower the plow-shares or their carrying-structure and in which provision is made for adjusting the angle and position of the furrow-wheel.

60 The invention is not to be understood as restricted to the details set forth, since these may be modified within the scope of the appended claims, without departing from the spirit and scope of the invention.

65 Having thus described my invention, what

I claim as new, and desire to secure my Letters Patent, is:

1. In a plow, the combination of a plow-carrying structure, carrying-wheels including a furrow-wheel, plow-shifting mechanism comprising a crank between said furrow-wheel and the carrying-structure, a bracket mounted on the crank and shifted vertically relatively to said structure when the crank is operated, said bracket having 70 an opening extending transversely therethrough and a spindle for said furrow-wheel, extending transversely through and fixedly and adjustably held in the opening in said bracket.

2. In a plow, the combination of a plow carrying structure, carrying-wheels including a furrow-wheel, plow-shifting mechanism comprising a crank between said furrow wheel and the carrying-structure, a 85 spindle for said furrow wheel, means for causing the spindle to remain at a constant angle during the shift of the crank, and means for longitudinally adjusting the spindle.

3. In a plow, the combination of a plow carrying structure, carrying-wheels including a furrow-wheel, plow-shifting mechanism comprising a crank between said furrow-wheel and the carrying structure, a 95 spindle for said furrow-wheel, means for causing the spindle to remain at a constant angle during the shift of the crank, and screws for angularly adjusting the spindle.

4. In a plow, the combination of a plow 100 carrying structure, carrying-wheels including a furrow wheel, plow-shifting mechanism comprising a crank between said furrow wheel and the carrying structure, a spindle for said furrow wheel, means for 105 causing the spindle to remain at a constant angle during the shift of the crank, and means for angularly and longitudinally adjusting the spindle.

5. In a plow, the combination of a plow- 110 carrying structure, carrying-wheels including a furrow-wheel, plow-shifting mechanism comprising a crank between said furrow-wheel and the carrying-structure, a spindle for said furrow-wheel, a bracket pivoted to and raised and lowered relatively to said structure by the crank, a spindle for the furrow-wheel longitudinally adjustable and fixedly held in said bracket, and means for preventing angular movement of the bracket 120 when the crank-arm is shifted.

6. In a plow, the combination of a plow-carrying structure, carrying-wheels including a furrow-wheel, plow-shifting mechanism comprising a crank between said furrow-wheel and the carrying-structures, a spindle for said furrow-wheel, a bracket pivoted to and raised and lowered relatively to said structure by the crank, a spindle for the furrow-wheel longitudinally adjustable and 125 130

fixedly held in said bracket, and a link between the bracket and the structure for preventing angular movement of the bracket when the crank-arm is shifted.

5 7. In a plow, the combination of a plow-carrying structure, carrying-wheels including a furrow-wheel, a plow-shifting mechanism comprising a crank between said furrow-wheels and the carrying-structure, a spindle for said furrow-wheel, a bracket pivoted to and raised and lowered relatively to said structure by the crank, a spindle for the furrow-wheel angularly adjustable fixedly held in said bracket, and means for preventing angular movement of the bracket when the crank-arm is shifted.

10 8. In a plow, the combination of a plow-carrying structure, carrying-wheels including a furrow-wheel, plow-shifting mechanism comprising a crank between said furrow-wheels and the carrying-structure, a spindle for said furrow-wheel, a bracket to which the crank is pivoted, a spindle for the furrow-wheel in said bracket, screws for adjustably holding the spindle in the bracket, and means for preventing angular movement of the bracket when the crank-arm is shifted.

15 9. In a plow, the combination of a plow-carrying structure, mechanism for shifting the structure, carrying-wheels including a furrow-wheel, a spindle on which said furrow-wheel is mounted, a bracket in which the spindle is held and connected to the shifting mechanism so as to be lowered relatively to the structure by said mechanism, and means for angularly adjusting and securing the spindle in the bracket.

20 10. In a plow, the combination of a plow-carrying structure, mechanism for shifting the structure, carrying-wheels including a furrow-wheel, a spindle on which said furrow-wheel is mounted, a bracket in which the spindle is held, and screws for angularly adjusting the spindle in the bracket.

25 11. In a plow, the combination of a plow-carrying structure, mechanism for shifting said structure, carrying-wheels including a furrow-wheel, a spindle on which said furrow-wheel is mounted, a bracket in which the spindle is angularly and longitudinally adjustable and screws for securing the spindle in the bracket.

30 12. In a plow, the combination of a plow-carrying structure, mechanism for shifting the structure, carrying-wheels including a furrow-wheel, a spindle on which said furrow-wheel is mounted, a bracket in which the spindle is longitudinally adjustable, and a screw securing the spindle in the bracket.

35 13. In a plow, the combination of a plow-carrying structure, carrying-wheels including a furrow-wheel, plow-shifting mechanism comprising a crank between said furrow-wheel and the carrying-structure, a

40 bracket operated vertically relatively to said structure by said crank, and a spindle for said furrow-wheel longitudinally adjustable and fixedly held in said bracket.

45 14. In a plow, the combination of a plow-carrying structure, carrying-wheels including a furrow-wheel, plow-shifting mechanism comprising a crank between said furrow-wheel and the carrying-structure, a bracket to which said crank is pivoted, a spindle for said furrow-wheel in said bracket and screws for angularly adjusting the spindle in the bracket.

50 15. In a plow, the combination of a plow-carrying structure, carrying-wheels, including a furrow-wheel, plow-shifting mechanism comprising a crank between said furrow-wheel and the carrying-structure, a bracket to which said crank is pivoted, a spindle for said furrow-wheel longitudinally adjustable in said bracket, and means for angularly adjusting the spindle in the bracket.

55 16. In a plow, the combination of a plow-carrying structure, carrying-wheels including a furrow-wheel, plow-shifting mechanism comprising a crank between said furrow-wheel and the carrying structure, a bracket to which said crank is pivoted, a spindle for said furrow-wheel angularly and longitudinally adjustable in said bracket, and a link substantially parallel with said crank and pivoted to said structure and said bracket.

60 17. In a plow, the combination of a plow-carrying structure, carrying-wheels including a furrow-wheel, plow-shifting mechanism comprising a crank between said furrow-wheel and the carrying-structure, a bracket to which said crank is pivoted and having a tapered opening therein, a spindle for said furrow-wheel in said opening, and screws for angularly adjusting the spindle in the bracket.

65 18. In a plow, the combination of a plow-carrying structure, carrying-wheels including a furrow-wheel, plow-shifting mechanism comprising a crank between said furrow-wheel and the carrying-structure, a bracket to which said crank is pivoted, having a tapered opening therein, a spindle for said furrow-wheel in said opening, screws for angularly adjusting the spindle in the bracket, and a connection between the bracket and the structure for causing it to retain a parallel position when the crank is operated.

70 19. In a plow, the combination of a plow-carrying structure, carrying-wheels including a furrow-wheel, plow-shifting mechanism comprising a crank between said furrow-wheel and the carrying-structure, a bracket to which said crank is pivoted, having a tapered opening therein, a spindle for said furrow-wheel in said opening and longitudinally adjustable therein, screws for

securing the spindle in the bracket, and a connection between the bracket and the structure for causing it to retain a parallel position when the crank is operated.

5 20. In a plow, the combination of a plow-carrying structure, carrying-wheels including a furrow-wheel, plow-shifting mechanism comprising a crank between said furrow-wheel and the carrying-structure, a
10 bracket to which said crank is pivoted, hav-

ing a tapered opening therein, a spindle for said furrow-wheel in said opening, screws adjacent one end of said opening for angularly adjusting the spindle in the bracket and a screw adjacent the other end of the 15 opening for securing the spindle.
